CLAIM

The ornamental design for a home network gateway, as
shown and described.

DESCRIPTION

FIG. 1 is a top and front perspective view of a home network
gateway showing my new design;

FIG. 2 is a front elevation thereof;

FIG. 3 is a rear elevation thereof;

FIG. 4 is a left side elevation thereof, the side opposite being
a mirror image;

FIG. 5 is a top plan view thereof; and,

FIG. 6 is a bottom plan view thereof.
